COMBINED ANESTHETIZING AND RESUSCITATING UNIT

Philip L. Stanton, Pasadena, Calif.

Application May 24, 1957, Serial No. 46,336

Term of patent 14 years

(Cl. D83—1)

Fig. 1 is an elevational view of one side of a combined anesthetizing and resuscitating unit showing my new design;

Fig. 2 is an elevational view of another side thereof;

Fig. 3 is an elevational view thereof as seen from the side opposite the side shown in Fig. 1;

Fig. 4 is an elevational view thereof as seen from the side opposite the side shown in Fig. 2; and

Fig. 5 is a top plan view of the combined anesthetizing and resuscitating unit.

The dominant feature of my design resides in the portions shown in full lines.

I claim:

The ornamental design for a combined anesthetizing and resuscitating units, as shown and described.
